Their ATTORNEY.

UNITED STATES PATENT OFFICE.

MERIT L. COCHRAN AND MARION E. WOOD, OF KANSAS CITY, KANSAS.

RAIL-JOINT.

1,396,558.

Specification of Letters Patent.

Patented Nov. 8, 1921.

Application filed November 8, 1920. Serial No. 422,421.

To all whom it may concern:

Be it known that we, MERIT L. COCHRAN and MARION E. WOOD, citizens of the United States, residing at Kansas City, in the county of Wyandotte and State of Kansas, have invented a certain new and useful Improvement in Rail-Joints, of which the following is a specification.

Our invention relates to rail joints. It 10 relates particularly to a novel rail chair and a novel means for attaching two rails to the chair.

An object of our invention is to provide a rail chair which is simple in construction, 15 cheap to make, durable, and efficient in operation.

A further object of our invention is to provide novel means for securely fastening two rails to a rail chair.

20 The novel features of our invention are hereinafter fully described and claimed.

In the accompanying drawing, which illustrates the preferred embodiment of our invention,

25 Figure 1 is a perspective view of our improved rail chair.

Fig. 2 is a perspective view of a U-bolt adapted to be used in connection with the chair.

30 Fig. 3 is a side elevation of our improved rail chair shown in operative engagement with two rails.

Fig. 4 is a top view of the same.

Fig. 5 is an end elevation, enlarged, of 35 the same, one of the rails being shown in cross-section.

Similar reference characters designate similar parts in the different views.

Our improved rail chair is provided with 40 a flat horizontal base 1 adapted to be supported on a tie 2 to which the chair may be rigidly attached in any desired manner, as by means of a spike 3 extending through a vertical hole 4 in the base 1 adjacent to

45 one side edge of the base 1, and by spikes 5 extending through edge notches 6 in the opposite side edge of the base.

The rail chair is provided with two flanges 7 and 8 which extend upwardly and inwardly 50 and are adapted to bear upon the upper sides of the bases 9 of two rails, the adjoining end portions of which are adapted to rest upon the base 1. The flanges 7 and 8 extend from the rail bases 9 upwardly at op-

posite sides respectively of and spaced apart 55 from the webs 10 of the two rails. The upper ends of the flanges 7 and 8 are, preferably, outwardly turned and bear against the under side of the balls 11 of the rails.

A horizontally disposed U-bolt provided 60 with two screw threaded arms 12 which are adapted to extend through the flanges 7 and 8 and through the two webs 10 of the rails is provided.

Respectively mounted on the threaded 65 arms 12 are two nuts 13 adapted to bear against the outer side of the flange 8. The transverse portion 14 of the U-bolt is adapted to bear against the outer side of the flange 7. 70

By employing a U-bolt for clamping the flanges 7 and 8 to the rails, possibility of the bolt being turned by vibration is avoided. Having the flanges 7 and 8 spaced apart from the webs 10, when the nuts 13 are 75 tightened, effects a spring clamping action of the flanges against the rails, which spring clamping action tends to hold the nuts 13 from being loosened through vibration of the parts. 80

By having the flanges 7 and 8 bearing against the upper sides of the bases of the rails and against the under sides of the balls of the rails, the flanges strongly reinforce the webs of the rails at the ends of 85 the rails.

In applying a chair to the rails, the chair is slipped on to one end of one of the rails, after which the adjoining end of the other rail is slipped between the flanges 7 and 8 in an 90 endwise direction. The arms 12 of the U-bolt are then passed through the holes provided therefor in the webs 10 and the flanges 7 and 8. The nuts 13 are then applied to the arms 12 and are so adjusted as to draw the flanges 7 and 8 toward each other, so as to create a spring clamping action of the flanges against the rails. 95

The base 1 of the chair is then spiked to the top of a tie 2, as already described. 100

The U-bolt 14 serves also to hold the rails against movement away from each other without any dependence being placed upon the flanges 7 and 8 for effecting this function, such as would be required were two ordinary bolts substituted for the U-bolt. 105

We do not limit our invention to the structure shown and described, as many modifi-

cations, within the scope of the appended claim, may be made without departing from the spirit of our invention.

What we claim is:

- 5 In a rail joint, a rail chair having a flat base adapted to support the bases of two adjoining rails and having respectively adjacent to opposite ends spike openings, and having intermediate of said openings two flanges adapted to embrace the upper sides of the bases of the rails and the under sides of the balls of the rails at opposite sides respectively of and spaced apart from the webs of the rails, the upper ends of the 10 flanges being outwardly turned and bear-
- 15

ing against the balls of the rails, and a U-bolt having threaded arms adapted to extend through said flanges and said webs and provided respectively with nuts adapted to bear against the outer side of one of said flanges, the longitudinal portion of the U-bolt being adapted to bear against the outer side of the other flange, whereby the flanges may exert a spring clamping action, substantially as set forth. 20 25

In testimony whereof we have signed our names to this specification.

MERIT L. COCHRAN.
MARION E. WOOD.
